F. B. ALLDREDGE,

DEVICE AND PROCESS FOR AUTOMATICALLY PREVENTING THE ACCUMULATION OF WATER IN GAS WELLS,
FILED DEC. 29, 1919.

Patented Dec. 19, 1922.

UNITED STATES PATENT OFFICE.

FRANCIS B. ALLDREDGE, OF DES MOINES, IOWA.

DEVICE AND PROCESS FOR AUTOMATICALLY PREVENTING THE ACCUMULATION OF WATER IN GAS WELLS.

Application filed December 29, 1919. Serial No. 348,040.

To all whom it may concern:

Be it known that I, FRANCIS B. ALLDREDGE, a citizen of the United States, and a resident of Des Moines, in the county of Polk and State of Iowa, have invented a certain new and useful Device and Process for Automatically Preventing the Accumulation of Water in Gas Wells, of which the following is a specification.

10 The object of my invention is to provide a device and process for automatically preventing the accumulation of water in gas wells.

15 A further object of my invention is to provide a means for taking the gas out of wells, lines or receptacles, and for drawing water, oil or other liquids out with it, and for then automatically separating the water or liquids from the gas.

20 A further object is to provide such a device in which the escape of gas is prevented by means of a water seal.

25 A further object is to provide a process for taking the gas and water from the well, and then separating the gas and water and disposing of the water.

With these and other objects in view my invention consists in the practice of the process hereinafter more fully set forth, pointed out in my claims and illustrated in the accompanying drawings, in which:

30 Figure 1 shows a vertical, central, sectional view through a gas well equipped with a device embodying my invention, and adapted for use in practicing my process.

35 Figure 2 shows an enlarged, sectional view of the upper part of the well, illustrating the arrangement of the pipes and the blow-off vent.

40 Figure 3 shows a horizontal, sectional view taken on the line 3—3 of Figure 1.

45 Figure 4 shows a sectional view of the water seal device taken on the line 4—4 of Figure 3.

Figure 5 shows a horizontal, sectional view taken on the line 5—5 of Figure 2.

50 Figure 6 shows a vertical, sectional view taken on the line 6—6 of Figure 5; and

Figure 7 shows a detail view of the blow-off control valve.

In the drawings herewith whereby my invention is illustrated, I have used the reference numeral 10 to indicate generally the ground in which the well is located.

In the ground is the hole or well in which 55 is received the ordinary casing 11.

Received in the casing and projecting downwardly below the casing is a suitable tube 13. Somewhere, preferably near the lower end of the casing, there is provided a 60 packer 14 around the tube 13 for closing the passage in the casing around the tube.

Extending downwardly through the tube 13 is a gas take-off pipe 15 which takes in the gas 65 at its lower end. At the upper end of the pipe 15 is a controlling valve 16. Leading from the valve 16 is a conducting pipe 17 which communicates with a sediment or settling tank 18 above the bottom thereof. Leading from the top of the tank 18 is the pipe 19 by 70 which the gas is taken away.

Leading from the bottom of the tank 18 is a pipe 20 which extends downwardly into the well between the casing 11 and the tube 13, as illustrated in Figures 1 and 2.

75 At the lower end of the pipe 20 is an elbow or the like 21 which extends approximately half way around the interior of the casing and is connected with an upwardly extending pipe 22. The pipe 22 at its upper end at 80 the top of the well connects with a water discharge pipe 23.

In the pipe 22 is mounted a three-way valve 24, which in one of its positions, allows free passage through the pipe 22, and in another position connects the lower part of the pipe 22 with a vent opening 25 in the pipe 22.

85 On the stem of the valve 24 is an arm 26. Wires 27 and 28 are connected with the opposite ends of the arm 26 and are so arranged that by pulling on one of said wires the valve can be set in one of its positions, and by pulling on the other of said wires the valve can be set in the other of its positions.

90 The pipe 15 at its upper end passes through a packing box 29 whereby the passage or opening between the pipe 15 and the tubing 13 is closed.

I will now explain the practical operation 100 of my improved device, and in connection therewith will explain the steps of my process and the manner of installing the pipes 20 and 22, and will explain the depths to which said pipes should extend into the well.

105 It is well-known that in gas wells one frequent source of trouble is the fact that water collects in the bottom of the well, finally ris-

ing to such a height that the gas cannot force its way through the water and the flow of gas is shut off.

In some instances by the process of "blowing out" the well every day or so, the well can be kept clean from such an amount of water as would stop the flow of gas. However, it very frequently occurs that the water accumulates so rapidly as to stop the gas flow, and in that case it is sometimes necessary to pull the tubing and bail out the well. Where it is necessary to pull the tubing there is involved a great expense and sometimes the well is spoiled.

15 Where my device is used I use the pipe 15 for taking the gas from the well, and close the passage between the pipe 15 and the tubing and also the passage between the tubing and the casing. When this is done the pressure of the gas will naturally tend to force the water out with the gas and as the gas comes from the well it carries with it a proportion of water depending upon the amount of water tending to collect in the bottom of 20 the well. The water level will naturally be maintained at the intake end of the pipe 13.

The water and gas pass into the tank 18, whereupon the water will stay in the bottom of the tank 18 and the gas will pass upwardly and away through the pipe 19. The water in the tank 18 will naturally flow downwardly through the unobstructed pipe 20 and will seek its level in the pipe 22.

In the absence of pressure in the tank 18 35 it is obvious that any accumulation of water in the tank would be avoided by the tendency of the water to seek its level. I am assuming, of course, that the pipe 23 does not rise above the level of the bottom of the tank 18. 40 However, it will be observed that there is constant pressure in the tank 18 due to the pressure of the gas in the well, and this pressure will force the water downwardly into the pipe 20 a certain distance depending upon the pressure of the gas.

By following the ordinary tables showing the equivalents of pressure and head of water it is easy to determine how far the gas pressure will force the water downwardly 50 into the pipe 20.

In controlling the device the lower end of the pipe 20 is always placed substantially below the farthest point to which the gas pressure will force the water.

55 By extending the pipes 20 and 22 below said point there will always be water in the member 21 and in the lower ends of the pipes 20 and 22 which will form a water seal and prevent the undesirable escape of gas.

60 The member 21 forms a sort of sediment collector.

The water seal structure at the lower end of the pipes 20 and 22 may be made by connecting said lower ends by a cross pipe 21 65 shown in Figure 4. Where this form of the

device is used I preferably extend short pipes 20^c and 20^d downwardly from the connecting pipe 21 for drip pipes and sediment collectors.

I install the valve 24 for blowing out any sand or sediment that might collect in the member 21.

The valve 24 is located at such a point in the pipe 22 that the column of water in the pipe 22 will not be sufficient to retain the gas and maintain the water seal, and the gas will force the water out through the vent 25, when the valve 24 is turned to proper position, and will blow the sediment out of the member 21.

In the use of my improved device, the pipes 20 and 22 are filled with water before the gas is allowed to flow into the tank 18 for causing pressure therein.

It will, of course, be understood that in the ordinary operation of the device the valve 24 is turned to position for closing the vent 25. The operation of the device is then as hereinbefore described.

Any water tending to accumulate in the tank will, of course, be immediately forced downwardly into the pipe 20, and any surplus will be forced out through the pipe 22.

The member 21 may be blown out at any time by simply manipulating the valve 24 for opening the vent 25.

After the blowing out process the gas can be shut off, the valve 24 turned to position for closing the vent 25, and the pipes 20 and 22 filled with water before the gas is again turned on.

It will be seen that the practice of my process involves the use of a pipe for taking off the gas small enough so that the pressure of the gas in the well will carry out the water as it accumulates with the flowing gas. The well must be closed so that the pressure is utilized for driving the water up through the pipe. Of course the well is always closed in any event to prevent the escape of gas.

The gas and water must be passed into a separate receptacle of some sort, and the water then allowed to flow into a pipe extending downwardly a proper distance, and there must be both a downwardly extending pipe and a return pipe so as to provide the water seal.

It is obvious that it is not necessary that the pipes 20 and 22 be placed in the well, but this is done simply for convenience and to avoid the necessity of digging a hole or raising the separating tank a sufficient distance above the ground. I can use my structure for taking gas, oil and water from a well. My device may be modified slightly and used for separating gas from water and other liquids in a pipe line or tank or other receptacle.

It is obvious that changes might be made in the construction and arrangement of the

parts of my device which embody my mechanical invention, and that there may be some changes in the details of the practice of the process without departing from the real purpose and spirit of my invention, and it is my intention to cover any variations in the structure of the mechanical part or the practice of the process which may be reasonably included within the scope of my claims.

10 I claim as my invention:

1. The process of taking gas and liquid from a place or receptacle containing the same, where said gas is under pressure and of cleaning the take-off means, comprising 15 the subjecting of the liquid at its surface to the movement of the passing current of gas, and thereby forcing the gas and liquid through a pipe, the discharging of the gas and liquid into a receptacle above the bottom thereof, the allowing of the flow of the gas from the upper part of said receptacle, the allowing of the liquid to flow from the lower part of said receptacle, and passing it 20 through a tube or the like, having a downwardly extending portion and an upwardly extending portion, whereby a liquid seal is formed at the bottom of said tube for preventing the escaping of gas from the last-named receptacle, and the subjection of said 25 upwardly extending portion directly to communication with the gas under pressure in said receptacle for blowing out said portion.

2. A device for handling gas and liquids, comprising a pipe adapted to be projected 30 into a means where gas and liquid are contained under pressure to a point where the intake end of the pipe is substantially at the surface of the liquid, means for closing the opening around said pipe, so that the pressure of the gas forces the gas and liquid therewith through said pipe, a receptacle 35 communicating above its bottom with said pipe, a take-off pipe leading from the top of said receptacle, a liquid discharge pipe 40 communicating with the bottom of said receptacle, and extending downwardly and thence upwardly, whereby the contents of 45 said receptacle, and extending downwardly and thence upwardly, whereby the contents of

the receptacle are under substantially the pressure imparted from the pressure of the gas, the lower parts of said last-described 50 pipe forming means for producing a liquid seal and permitting the flow of liquid from said receptacle, but preventing the escape of gas under pressure therein through said liquid discharge pipe and means for placing the take-off pipe directly in communication with the gas under pressure, for cleaning out purposes.

3. A device for handling gas and liquids, comprising a pipe adapted to be projected 60 into a means where gas and liquid are contained under pressure to a point where the intake end of the pipe is substantially at the surface of the liquid, means for closing the opening around said pipe, so that the 65 pressure of the gas forces the gas and liquid therewith through said pipe, a receptacle communicating above its bottom with said pipe, a take-off pipe leading from the top of said receptacle, a liquid discharge pipe 70 communicating with the bottom of said receptacle, and extending downwardly and thence upwardly, whereby the contents of the receptacle are under substantially the 75 pressure imparted from the pressure of the gas, the lower parts of said last-described pipe forming means for producing a liquid seal and permitting the flow of liquid from said receptacle, but preventing the escape of gas under pressure therein through said 80 liquid discharge pipe, the upper stretch of said last-described pipe having a discharge opening and a three-way valve adapted in one position to close said last opening and to permit the flow of liquid through the pipe 85 and in another position to close the passage through the pipe and to permit the passage of liquid through said discharge opening, whereby the pressure in said receptacle may be used for blowing out the contents of the 90 liquid discharge pipe.

Des Moines, Iowa, November 5, 1919.

FRANCIS B. ALLDREDGE.
